UNITED STATES PATENT OFFICE.

BONA ALLEN, JR., OF BUFORD, GEORGIA.

NONSLIP BELT.

1,420,604.

Specification of Letters Patent. Patented June 20, 1922.

Application filed June 6, 1921. Serial No. 475,512.

To all whom it may concern:

Be it known that I, BONA ALLEN, Jr., a citizen of the United States, residing at Buford, in the county of Gwinnett and State of Georgia, have invented certain new and useful Improvements in Nonslip Belts; and I do hereby declare the following to be a full, clear, and exact description of the invention, such as will enable others skilled in the art 10 to which it appertains to make and use the same.

The present invention relates to improvements in non-slip belts and has for an object to provide a belt with a series of shoulders 15 against which the buckle tooth may actively engage to avoid the likelihood of the belt slipping therethrough.

Another object of the invention resides in providing an improved non-slip belt, the 20 construction of which is simple and inexpensive and which may be provided with shoulders without altering materially the construction of standard belts and without detracting from the appearance of the same.

25 With the foregoing and other objects in view, the invention will be more fully described hereinafter, and will be more particularly pointed out in the claims appended hereto.

30 In the drawings, wherein like symbols refer to like or corresponding parts throughout the several views,

Fig. 1 is a perspective view of one form of non-slip belt constructed according to the 35 present invention;

Fig. 2 is a fragmentary view of the inside portion of the belt and buckle with parts shown in section;

Fig. 3 is a plan view thereof;

40 Fig. 4 is a horizontal sectional view taken through the buckle and adjacent parts of the belt;

Fig. 5 is a similar view showing a slightly modified construction of belt; and

45 Fig. 6 is a fragmentary perspective view of the belt shown in Fig. 5.

Referring more particularly to the drawings, and for the present to Figs. 1 to 4 inclusive, the belt herein shown is made up of an outer ply 1 and an inner ply 2 which, as indicated in Figs. 1 and 2, are secured along their upper and lower edges by lines of stitching 3 and 4 respectively.

The belt at one end is returned upon itself 55 to provide a loop 5 to which a lever 6 is secured. A buckle plate 7 is carried by the

lever and pivotally associated therewith as represented at 8, the buckle tooth 9 being secured to and turning with the lever 6, the same being disposed at substantially a right angle to the plane of the lever as represented in Fig. 4. The free end of the belt slides through the buckle plate 7 in the usual manner and as represented in Fig. 4 and is adapted to be caught and wedged by the action of the tooth 9 against the inner face of said buckle plate. The action is such that when strain is put upon the belt tending to loosen the same the tooth 9 will bite more effectively into the belt and avoid its slipping. However, this is not entirely practicable with belts of this general character and to constitute a more positive binding engagement between the tooth 9 and the buckle plate 7 I provide shoulder portions on the belt against which the tooth may more actively engage and which shoulder portions are larger than the distance between the tooth and inner face of the buckle plate when the tooth is in the operative position illustrated in Fig. 4.

In the form of the invention shown in Figs. 1 to 4 I provide these shoulder portions by inserting strips 10 of leather, fabric or other material at the required intervals, such strips being confined between the plies 1 and 2 of the belt and being secured as by vertical lines of stitching 11 for instance to the inner ply 2 so that the stitching will not be apparent on the outside surface of the belt 90 which might otherwise be undesirable or detract from the appearance of the belt.

These strips 10 need only be of a very narrow width, just sufficient to furnish that necessarily rigid shoulder which will co-act 95 with the tooth 9 to prevent any possible slipping of the belt. These strips may be provided in any suitable numbers and at suitably spaced distances. They may also be of any desired length.

100 Referring more particularly to Figs. 5 and 6, a different type of belt is shown which comprises a solid body 12 made up of a single piece of relatively thick leather or other suitable belt material. In this instance I carry out the invention by making vertical 105 grooves 13 in the inner face of the belt near its free end, the walls of these grooves forming the necessary shoulder to take against the tooth 9 of the belt. It will also of course 110 be understood that the shoulders may be formed in numbers of different ways.

It is obvious that various changes and modifications may be made in the details of construction and design of the above specifically described embodiment of this invention without departing from the spirit thereof, such changes and modifications being restricted only by the scope of the following claims.

What is claimed is:—

- 10 1. An improved belt having a buckle secured at one end and provided with a buckle tooth, said belt composed of inner and outer plies secured together, and numbers of strips secured between the inner and outer plies 15 and forming shoulders adapted to be en-

gaged by said tooth of the buckle, substantially as described.

2. The combination with a belt provided with a series of transverse shoulders near the free end thereof, of a buckle secured to the opposite end of said belt and comprising a plate with inwardly projecting jaws, and a bell crank lever pivoted between said jaws and having an eye connected to said belt and having a broad engaging arm adapted to engage one of said shoulders formed in said belt when said belt is in use, substantially as and for the purpose described.

BONA ALLEN, JR.
